UNITED STATES PATENT OFFICE

JOHN H. PHILLIPS, OF CHICAGO, ILLINOIS

ANCHORING DEVICE

Application filed May 29, 1925. Serial No. 33,774.

My invention relates to anchoring devices and particularly to expandible anchor bolts. The invention has among its other objects the production of a device of the kind described, 5 which is simple, convenient, reliable, inexpensive and satisfactory for use wherever found applicable. A particular object of the invention is to provide an improved self-drilling device of the kind described which 10 can be manufactured at a relatively low cost. Another particular object of the invention is to provide an improved device of the kind described which can be used in connection with standard pipe fittings and the like.

15 In accordance with the features of the invention, tubular expansible anchor bolts are formed from pipes, tubes or the like and each is provided with drill teeth at one end and pipe threads at the other end. Preferably, 20 each bolt is threaded for a greater distance than is the conventional practice. The threaded ends of said lengths are then tapered so that the lengths may be seated in 25 chucks or the like to permit them to be used as drills. In the preferred embodiment of the invention the lengths are provided with slots intermediate their ends to form weakened 30 portions adjacent the drill teeth so that the devices may be easily expanded to secure them in walls and the like. After the bolts 35 have been secured in a wall, standard pipe fittings or the equivalent may be secured thereto to secure other articles or apparatus to the bolts.

25 Many other objects and advantages of the construction herein shown and described will be obvious to those skilled in the art from the disclosure herein given.

40 To this end my invention consists in the novel construction, arrangement and combination of parts herein shown and described and more particularly pointed out in the claims.

45 In the drawings, wherein like reference characters indicate like or corresponding parts:

Figure 1 is a longitudinal section through an anchoring device embodying my invention, the anchoring device being shown in

connection with a chuck in which it is adapted to be seated;

Figure 2 shows my improved anchoring device firmly fixed in a ceiling or the like and provided with a coupling member whereby 55 it supports a load;

Figure 3 is an enlarged longitudinal section taken substantially on the same line as Figure 1 but showing in more detail certain features 60 of construction; and

Fig. 4 is a section taken on line 4-4 of Fig. 1.

Referring to the drawings, wherein I have shown a preferred form of the invention, the reference character 15 designates a tubular shell which is formed of any suitable material such as pipe, tubes, or a plate. In some instances, the tubular shell may be cast, and in other instances may comprise complementary sections embodying the features of the invention. The tubular shell 15 is provided at one end with a plurality of cutting teeth 16 and 17, or the equivalent. At its other end it is preferably pipe threaded as at 18. The pipe threads 18 preferably extend a greater distance along the tubular shell 15 than is the conventional practice in the threading of pipes and the like, but in some instances I may form a shorter thread upon the shell. The threaded end of the shell is shown tapered, as at 20, so that the shell may be seated in a tapered aperture 21 formed in a chuck 22. As best illustrated in Figure 3, the shell is so tapered at its threaded end that the shell 25 may be inserted in the tapered aperture 21 without injuring the pipe threads 18. Thus the smallest diameter of the tapered portion is substantially equal to the smallest diameter 30 at the base of the pipe threads. The chuck 22 may be formed with a plurality of intersecting bores 24 and 25. This permits material cut by the drill teeth 16 and 17 to pass through the shell 15 and out through the bores 24 and 25, and also permits the shell to be unseated 35 from the chuck by the insertion of a key into one of the bores 24 and 25. Intermediate its ends the shell 15 is preferably provided with a plurality of slots 27 or the equivalent 40 which form weakened portions 28 adjacent

45 the base of the pipe threads. The chuck 22 50 may be formed with a plurality of intersecting bores 24 and 25. This permits material cut by the drill teeth 16 and 17 to pass through the shell 15 and out through the bores 24 and 25, and also permits the shell to be unseated 55 from the chuck by the insertion of a key into one of the bores 24 and 25. Intermediate its ends the shell 15 is preferably provided with a plurality of slots 27 or the equivalent 60 which form weakened portions 28 adjacent 65 the base of the pipe threads. The chuck 22 70 may be formed with a plurality of intersecting bores 24 and 25. This permits material cut by the drill teeth 16 and 17 to pass through the shell 15 and out through the bores 24 and 25, and also permits the shell to be unseated 75 from the chuck by the insertion of a key into one of the bores 24 and 25. Intermediate its ends the shell 15 is preferably provided with a plurality of slots 27 or the equivalent 80 which form weakened portions 28 adjacent 85 the base of the pipe threads. The chuck 22 90 may be formed with a plurality of intersecting bores 24 and 25. This permits material cut by the drill teeth 16 and 17 to pass through the shell 15 and out through the bores 24 and 25, and also permits the shell to be unseated 95 from the chuck by the insertion of a key into one of the bores 24 and 25. Intermediate its ends the shell 15 is preferably provided with a plurality of slots 27 or the equivalent 100 which form weakened portions 28 adjacent

the teeth 16 and 17. The purpose of this construction will presently appear.

The shell 15 may be driven into a ceiling 30 or the like or into a wall formed of concrete, etc., the shell 15 being in the nature of a stone drill. To drive the shell 15 into the ceiling 30, the shell is seated in the chuck 22 and the chuck is attached to any suitable hammer device, whereby reciprocatory motion may be imparted to the shell, the shell being simultaneously rotated or oscillated. When driven into the ceiling, the shell 15 forms a substantially cylindrical hole 31 therein. After the shell 15 has been driven 15 the desired distance into the ceiling 30 it is removed therefrom and a tapered plug 32 is seated in the drill end thereof. The shell is again driven into the hole 31 and as it approaches the bottom of the hole will be expanded by the plug 32 in the manner illustrated in Figure 2, the hole 31 being enlarged at its bottom as indicated at 34. The shell 15 is then firmly fixed in the ceiling 30 and the chuck 22 may be removed therefrom.

25 A standard pipe fitting or any suitable coupling member 35 may be threaded upon the pipe threads 18 of the shell. A pipe section 36 may be threaded into the lower end of the coupling 35 to suspend a bracket member 37 30 threaded upon the lower end of the pipe section 36. The bracket member 37 may be of any suitable size and form but in this instance comprises an annulus 38 adapted to receive a pipe 40 which may be a gas or water pipe, or 35 other apparatus.

I do not limit myself to the use of the same shell 15 for drilling the hole 31 as for drilling the enlargement 34 at the bottom of the hole, as a plurality of substantially cylindrical holes 31 could be drilled with a drill shell 15 and shells of cheaper manufacture could be employed in the final drilling or reaming operation. Thus, if the drill shell 15 were made of a suitably hard material, it could be 40 employed for drilling a plurality of the holes 31. The anchoring devices finally secured in the holes 31 could be of cheaper form, although after the teeth of the drill shell 13 became worn, it could be used as an anchor 45 bolt in one of the holes.

50 Having thus described my invention, it is obvious that various immaterial modifications may be made in the same without departing from the spirit of my invention; hence I do 55 not wish to be understood as limiting myself to the exact form, construction, arrangement and combination of parts herein shown and described or uses mentioned.

What I claim as new and desire to secure 60 by Letters Patent is:

65 1. An expandible tubular shell embodying 70 drill teeth formed at one end thereof, an externally pipe-threaded portion for suspending 75 apparatus therefrom, a portion of said threaded portion being tapered for frictional-

ly engaging a chuck having a corresponding tapered socket, and weakened portions adjacent the drill teeth.

2. An anchor device comprising a tubular shell having drill teeth formed at one end thereof and having external pipe threads cut in the other end thereof, the initial portion of said threaded end being tapered to frictionally engage a chuck and the toothed end being weakened to permit expansion thereof.

In testimony whereof, I have hereunto signed my name.

JOHN H. PHILLIPS.
